UNITED STATES PATENT OFFICE.

FRANCIS J. CARNELLI, OF NEWARK, NEW JERSEY.

CHAIN WRENCH.

Application filed November 5, 1926. Serial No. 146,299.

This invention has reference to wrenches of the type known in the trade as chain pipe wrenches.

The main object of the invention is to provide a wrench of the chain type, wherein the chain is passed around the pipe or other object and secured to the body that carries a handle, and a handle being in a neutral position relative to the pipe, when the handle is swung in one direction it will quickly grip the pipe and turn it in that direction, and returning the handle to the neutral position, in which its axis would intersect the axis of the pipe, the pipe is released; and moving the handle and body while maintaining this position will permit a free movement of the pipe, and then moving the handle in the same direction as previously the pipe will be again gripped and turned; and which construction will without any change in the position of the pipe wrench or chain, by merely swinging the handle in the opposite direction relative to the neutral position, will cause rigid engagement with the pipe to turn it in the opposite direction; and swinging the handle back to neutral position will release the pipe when the wrench can be advanced to get another bite on the pipe and turn it in this direction a further distance.

A further object is to provide a device of this character in which a minimum amount of movement of the handle is necessary to cause a tight grip on the article, and a slight retraction will release the grip and permit another bite to be had on the article, and which movement is reversible to turn the article in either direction.

A further object of the invention is to provide a device of this character in which there are no relatively movable portions except the chain and its adjustable connections with the body of the wrench, whereby various sizes of articles can be engaged on a comparatively large range.

In the accompanying drawing illustrated is one embodiment of my invention:

Fig. 1 is a plan view of the wrench.

Fig. 2 is an edge view at one end.

Fig. 3 is a section enlarged on line 3—3 of Fig. 4.

Fig. 4 is a section in the line 4—4 of Fig. 3.

Fig. 5 is a section on the line 5—5 of Fig. 1.

Fig. 6 is an end view.

The device comprises essentially a body member that is provided with a jaw face; a handle member that is rigidly secured to the body member; and a chain member adjustably carried by the body member.

As shown I provide a handle member in the form of a bar 6. The body is in the form of two jaw plates 7 and 8 that are substantially duplicates, each having on the inner wall a slot portion, 9 and a hole 10. These plates are brought together on opposite sides of the end portion 11 of the handle bar, see Fig. 4, and a pair of bolts pass through the opening 10 and screw into threaded bore 12 in the bar 6, and rigidly clamp these three members together. Each of the jaw plates 7 and 8 is provided at the front end with angular faces 13 and 14, that extend at the same angle from the longitudinal axis of the handle bar 6, and which faces make a very wide or obtuse angle with each other, and are adapted to have the pipe or other article press against them. These four jaw faces are provided with teeth 15, preferably somewhat ratchet that extend outwardly.

The chain member of the device is in the form of a link chain 16, having means for engaging the body at various places along one portion or half of the chain, such as pins 17 projecting beyond the links on each side. Means are provided in the body for engagement with these pins on both sides, as shown the opposite inner walls 18 and 19 of the jaw plates 7 and 8 are provided with inwardly projecting lugs 20, and 21. It will be understood that any of these pivot pins 17 of the chain can be passed down in this slot in the body and engage these lugs 20, as shown in Fig. 3, and cannot draw out in the line of the handle.

The other end of the chain is adjustably mounted in the body member, as shown by means of a threaded stem 22 pivoted at one end to the end link 23, see Fig. 3. The body at this side of the handle has a slot extending parallel with the handle to admit the

chain and bolt. Slots 24, 25, are formed in the two members extending across this slot and admit a ring nut 26 threaded to engage the bolt 22.

It will be readily seen that the bolt can be inserted from the front end into this slot with the nut placed across the slot, and as the nut is turned the bolt will be drawn back toward the handle and draw on the chain, as shown in Fig. 3.

In the use of a device, the article such as a pipe 30 is placed against the jaws 13 and 14, see Fig. 3. The chain will be held at one end by the bolt and the free end is passed around the pipe, and then down into the slot containing the lugs 20, and the pins on the chain are passed into the slot between plates, and the nut ring 26 is turned to draw the chain into the body until it is comparatively taut on the pipe, with the wrench handle in the projecting out transverse to the pipe, that is, the axis of the handle intersecting the center of the pipe. Moving the handle relative to the pipe in either direction will cause the jaw on that side to press tight against the pipe, after a very limited or small swing of the handle from the neutral position, and a tight grip is had on the pipe to cause it to turn in such direction. Merely swinging the handle back to neutral position from this position will cause the engaged jaw to release, and keeping the handle in this neutral position the entire wrench can move back on the pipe free to engage the pipe at another location. Then the handle is given a swing in the same direction beyond the relative neutral position, and it will again grip the pipe and turn it further in the same rotative direction, which is the usual ratchet operation.

If it should be desired to turn this pipe or article in the opposite direction, it is not necessary to remove or adjust the wrench, but the handle is merely swung in the opposite direction from its neutral position from that just described. This will cause the other jaw, (in the direction to be turned), to grip the pipe, and a strong engagement will result to turn the pipe. Bringing the handle back to the neutral position will release from this jaw and permit the wrench and chain to move back for a grip in another position, then swinging the handle from the neutral position will grip the pipe and cause it to turn further, which is the usual ratchet operation.

A device of this character possesses great advantage over the forms of wrench wherein a relative movement is had between the handle and the jaw or body member. Sometimes a pipe is in a location rather inaccessible, and only a very limited swing of the handle is permitted. With my form of wrench the handle will grip the article on a swing a very short distance beyond the neutral position. Furthermore, this neutral position exists

when the wrench projects outwardly with the handle axis intersecting the axis of the pipe, in other words directly in front of the same. Another advantage is that the device is instantly reversible, and to turn the pipe in either direction, the wrench does not need to be removed and turned over to opposite position for use.

It will be further understood that the device is very simple and strong, comprising merely the handle to which the two jaw plates are secured, forming a very rigid compact construction. These members are secured by one or a pair of bolts. In addition the chain is merely added, being attached to the body at one end portion by merely inserting its pins in the slotted portion of the body; while the other end of the chain is attached by the easily adjustable bolt and nut. The latter can be unscrewed and the chain removed at any time and also the nut, after the other three members have been assembled.

It will be further seen that the chain when adjusted is supported at one end by the link connection with the bolt, which connection is brought in close proximity to the jaws where they engage the pipe. The other end of the chain has the pins on a link held by the opposite lug walls in the body, and this point of connection between the chain and the body, is also in close proximity to the pipe or other article. As has been explained, in operation the pipe is held practically in this position, and the chain will wrap itself around a comparatively large portion of the pipe practically up to the two places where the pipe is held by the jaws. It has been found that by this arrangement it is practically impossible in turning a pipe to crush or dent the pipe, and it is not injured in the operation. With other forms of pipe wrenches the chain engages a relatively small part of the pipe and the pipe often becomes distorted, or crushed.

What I claim is:

In a chain wrench, a body having a handle rigid therewith on one end, a jaw face on the opposite body end comprising two angular faces making an obtuse angle and provided with teeth, a chain having a threaded stem at one end, the body having a socket to receive the stem and also having an opening extending across said socket, a nut ring inserted in said socket to receive the threaded stem by turning the nut, the body member having on one side an open slot with lugs in the opposite slot walls, said lugs being arranged to form substantially U-shaped recesses opening laterally of the body, the chain having pins on opposite sides adapted to engage said lugs on insertion of the chain, whereby the chain can pass around a pipe or bar that engages said angular faces and be gripped thereon by said adjustment, said angular toothed faces

being arranged to grip the engaged member on either face alternately as the handle is swung from a transverse neutral position toward either side jaw, and to release when the handle is swung back to the neutral position, said chain supports being in close proximity to the jaw faces respectively

whereby the chain will enclose a very large part of the pipe and effect a very quick grip and release of the pipe, with very small 10 movement of the handle.

Signed at New York city, N. Y. on Nov. 4, 1926.

FRANCIS J. CARNELLI.
